PACKAGING CONTAINER OR SIMILAR ARTICLE

Mortimer D. Sackler, New York, N.Y., and Mordecai R. Craig, Demarest, N.J., assignors to Synergistics

Filed June 28, 1971, Ser. No. 157,807

Term of patent 14 years

Int. Cl. D9—01

U.S. Cl. D9—163

FIG. 1 is an elevational view of a packaging container or similar article embodying our new design;

FIG. 2 is an elevational view looking from the right of FIG. 1; and

FIG. 3 is a top plan view thereof.

We claim:

The ornamental design for a packaging container or similar article, as shown.
